ELECTRONIC COMPONENTS TEMPLET OR SIMILAR ARTICLE

Murray W. Kravis, Flushing, N. Y.

Application April 29, 1957, Serial No. 45,924

Term of patent 7 years

(Cl. D52—1)

The single figure shown in the drawing is a front view of an electronic components templet showing my new design.

The rear side of the templet not shown is substantially the same in appearance as the front shown.

The templet is of conventional thickness.

I claim:

The ornamental design for an electronic components templet or similar article, substantially as shown and described.
